UNITED STATES PATENT OFFICE.

JOHN B. MACFARLAND, OF VANCOUVER, BRITISH COLUMBIA, CANADA.

AEROPLANE.

Application filed March 17, 1925. Serial No. 16,228.

This invention relates to aeroplanes or airships of the heavier than air type, and one of its objects is to provide a machine of this character utilizing one or more revoluble series of elevating planes or paddles mounted for movement about an axis or axes extending transversely of the machine, each of said planes being so constructed and normally arranged as to produce the maximum displacement of air during the downward movement thereof and adapted to then move upwardly with practically no resistance from the atmosphere, whereby the aeroplane may be caused to ascend or descend substantially in a vertical direction, or to substantially hover over a given point.

A further object is to provide a revoluble series of planes which are shiftable about their transverse axes so that the driving power thereof can be varied at will and the machine readily caused to ascend or be propelled ahead as a result of the manipulation of said planes.

A still further object is to provide a machine which is compact, light and durable.

With the above general objects in view, and others that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a top plan view of an aeroplane constructed in accordance with the present invention.

Figure 2 is a side elevational view thereof.

Figure 3 is an enlarged fragmentary section taken substantially upon line 3-3 of Fig. 1.

Figure 4 is a fragmentary perspective view, partly broken away, of one of the planes and,

Figure 5 is a substantially central transverse section of one of the planes.

Referring more in detail to the drawings, the present invention includes an elongated main frame or body consisting of an upper rectangular rigid frame 5 and a lower or base frame 6 of similar form, which frames are rigidly connected in spaced superimposed relation by means of corner posts 7 and intermediate side posts 8 as best shown

in Figures 1 and 2. Braces 9 are employed between the frames 5 and 6 and the posts 7 and 8 so as to produce a rigid frame capable of withstanding all ordinary strains to which the machine may be subjected while in flight. Suitable seats 10 and 11 may be provided in the forward end portion of the frame in tandem relation for accommodating the operator of the machine and a passenger, and suitably pivoted centrally to the rear end of the main frame is a suitable vertical rudder 12 adapted to be swung laterally for changing the course of travel of the machine. For operating the rudder 12, rigid levers 13 may be provided upon the same so as to project laterally therefrom slightly rearwardly of the pivot of said rudder, and each of these levers is connected to a flexible member or cable 14, the forward ends of which cables are attached to opposite ends of a horizontally swinging foot lever 15 which is mounted intermediate its ends upon a vertical pivot 16 in front of the operator's seat 10. The main frame may be provided with supporting wheels 17 for facilitating landing as is well known in the art.

The machine shown is provided with two series of forward main elevating and propelling devices, one of which main series of elevating and propelling devices is located at each side of the upper forward portion of the main frame, and a single series of smaller rear auxiliary elevating and propelling devices located centrally of the rear upper portion of the main frame. For sake of clearness, the two series of main elevating and propelling devices are designated by the reference character 18, while the rear auxiliary series of elevating and propelling devices is generally indicated by the reference character 19.

The mechanism of each series of elevating and propelling devices consists of a transverse shaft 20 having each end projecting a substantial distance beyond one side of the frame, substantially setting up upon each side thereof a sub-shaft 20^a upon each of which is rigidly mounted a pair of spaced spiders having radial arms 21 disposed in equi-distant spaced relation. It will thus be seen that each elevating and propelling device includes a pair of members revoluble with their sub-shaft 20^a, and the outer ends of the arms of these members carries a stub shaft 22 which are journaled in suitable

bearings provided in the outer ends of the arms 21.

A variable speed motor, such as an internal combustion engine 23 is mounted upon the base frame 6 in front of the driver's seat 10 and has a sprocket wheel 24 secured upon its drive shaft. The shaft 20 of the forward main elevating and propelling devices are integrally connected as clearly shown in Figure 1, and fixed upon the connection of these shafts is a sprocket wheel 25 around which passes an endless sprocket chain 26 that also passes around the sprocket wheel 24 of the motor, whereby, upon operation of the motor, the shafts 20 of the forward main elevating and propelling devices, are rotated. It will thus be seen that the shafts and frames of the two forward main elevating and propelling devices will be simultaneously driven at a corresponding speed.

Secured upon the stub shafts 22 are the elevating and propelling planes, each of which consists of a pair of end members 27 each mounted upon a stub shaft 22 and rigidly connected in spaced parallel relation by means of front and rear transversely extending frame car members 28, the upper edges of the end members 27 being of upwardly bowed or curved form. The tops of these plane frames are covered by a reticulate fabric or screen covering 29 which overlies a plurality of uniformly spaced rods or wires 30 connecting the upper edge portions of the end members 27. The rods 30 support flaps 31 of silk or other suitable fabric, and these flaps are so proportioned as to swing against the wires 30 and lap one another when the plane is moving downwardly or in one direction, while, when said plane is moving upwardly or in another direction, the flaps will assume an open or vertical position and permit air to pass freely between them.

The inner ones of the stub shafts 22 of each plane have a crank 32 rigid therewith, and the cranks of each series of elevating and propelling planes are pivotally engaged in the outer ends of the rigid arms 33 of a spider which embodies a central eccentric ring 34 rotatably mounted on an eccentric disk 35 journaled upon the adjacent portion of the adjacent sub-shaft 20^a. With the eccentric disc 35 and gear 40 which is rigidly secured thereto mounted upon the shaft to freely rotate thereabout, it will be readily understood that upon securing the control chain 41, the eccentric disc will be held in any desired position so that when the arms 21 are rotated, the ring 34 will be caused to rotate the cranks 32 to maintain them in parallel relation at all times, as shown in Figure 3. Braces 36 connect the outer end portions of the arms or spokes 33.

The transmission of rotation to the rear auxiliary series of elevating and propelling

planes may be accomplished by any suitable gearing such as a longitudinal shaft 37 having its forward end operatively connected by a bevel gearing 38 to the main shaft 20 operating the main elevating and propelling devices, and having its rear end operatively connected to the shaft 20^c of the auxiliary elevating and propelling device by means of a bevel gearing 39. Obviously, a variable speed gearing may be interposed between the gearings 38 and 39 in order to vary the speed of rotation of the auxiliary elevating and propelling device in relation to that of the main elevating and propelling devices. This latter arrangement would facilitate changing of the course of the aeroplane vertically for expediting ascension or descension.

When the parts are normally disposed so that the elevating planes are constantly maintained parallel to the base frame 6, the aeroplane may be caused to substantially rise or descend in a vertical path, or may be caused to substantially hover over a given point.

As shown clearly in Figures 1, 2 and 3 the eccentric disk 35 of each of the main elevating and propelling devices is provided with a rigid sprocket wheel 40. In other words, a sprocket 40 is rigid with the eccentric disk 35 of each main elevating and propelling device, and passing around each sprocket 40 is an endless chain 41 which also passes around another sprocket wheel 42 suitably journaled at the adjacent side of the main frame of the machine, each sprocket 42 being provided with an operating shaft having a crank arm or handle 43 secured thereon. It is thus apparent that by swinging the handles 43 the sprocket wheels 40 may be rotated for shifting the eccentric disks 35 of the main elevating and propelling devices about the sub-shafts 20^a of the latter, whereby the angular relation of the elevating and propelling planes may be changed in regard to a horizontal plane or the base frame 6. In other words, the rotation of the eccentric disk 35 of each propelling and elevating device results in shifting of the elevating and propelling planes from their normal position wherein they are parallel to each other and to the base frame 6, to a position wherein the same are angularly related to the latter. Obviously, by thus shifting the planes, they may be positioned so that their impelling force will be exerted in different directions whereby the planes may be utilized either to cause direct ascension of the aeroplane or direct forward movement thereof, while further adjustments of the planes may be had for varying the action of the latter so that the same will simultaneously act to cause the aeroplane to ascend and move forward, the angle or degree of inclination of the path of ascension being variable at will. By permitting independent adjustment of the

planes of one series relative to those of another series, the course of travel of the aeroplane may be controlled as desired with a wide range of variation.

The shaft 20^p of the rear auxiliary series of elevating and propelling devices has a similar sprocket wheel 40' journaled thereon and rigid with the eccentric disk 35 thereof, and passing around this sprocket wheel 40' is an endless sprocket chain 41' which also passes around a sprocket wheel 44 suitably journaled upon the base frame 6 rearwardly of the passenger seat 11. The sprocket wheel 44 is mounted upon a shaft which also carries another similar sprocket wheel 44' around which passes a second endless sprocket chain 45, and the latter sprocket chain also passes around a still further sprocket wheel 46 suitably journaled at one side of the driver's seat 10. The sprocket wheel 46 is provided with a suitable operating lever 47 which may be swung by the driver for shifting the eccentric disk 35 of the rear auxiliary elevating and propelling device so as to change the angular relation of the planes of the latter with relation to a horizontal plane or the plane of the base frame 6. Thus the rear auxiliary elevating and propelling device may be utilized to assist the main devices in causing the forward travel or ascension of the aeroplane. While the arrangement of the elevating and propelling devices herein shown and described is believed to be preferable in order to secure proper longitudinal balance, it is to be understood that variation may be made in this arrangement of the devices without departing from the spirit of the invention. The main frame may be partially enclosed in any preferred or desired manner so as to provide a closed body or fuselage for the occupants of the seats 10 and 11, as will be apparent to those skilled in the art.

When it is desired to ascend, the motor 23 is placed in operation and the eccentric disks 35 of the several elevating and propelling devices are set as shown by full lines in the several views so that the planes are disposed parallel to each other and parallel to a horizontal plane. As these planes travel downwardly, the flaps 31 will swing upwardly against the rods or wires 30 as shown by full lines in Figure 5 so as to cause the downward displacement of the air and consequent upper movement of the machine, it being noted that the several sets of planes rotate in a similar direction. During the upward movement of each of the elevating planes, the flaps 31 are swung downwardly away from the wires 30 as shown in Figure 4 and by dotted lines in Figure 5 so as to permit the air to pass between them and thus offer practically no resistance to the upward movement of the plane. After the machine has attained a desired elevation it can be propelled either

forwardly or backwardly by shifting the eccentric disks 35 in the proper direction through the operation of the actuating handles 43 and 47. Should all of the planes be shifted to a similar degree, the machine will be driven in a straight path of travel but, by swinging the planes at one side of the machine or shifting them at one side to a greater extent than those at the other side, the machine can be turned to one side. This turning of the machine may be facilitated by actuation of the vertical rudder 12.

Obviously, by varying the speed of the motor 23 the speed of rotation of the series of planes may be varied so that the machine may be caused to substantially hover over a given point if desired.

From the foregoing description it is believed that the construction and operation as well as the advantages of the present invention will be readily understood and appreciated by those skilled in the art.

What I claim as new is:

1. A plane structure of the character described and for the purpose set forth comprising a pair of spaced parallel end members each having the upper edge thereof upwardly bowed, a plurality of spaced parallel rod members connecting said end members, a reticulate fabric overlying said rods and the bowed edges of said end members, a fabric flap supported by and extended throughout the length of each rod and adapted to swing upwardly against the under surface of said reticulate fabric, under certain conditions to prevent passage of air therethrough, said flaps separating and extending downwardly from their respective rods under certain other conditions, to permit air to pass through the reticulate fabric, substantially as and for the purpose described.

2. An aeroplane structure of the character described, comprising a frame, a revolute main shaft extending through and having each end projecting beyond one side of said frame, substantially setting up a pair of sub-shafts, one on each side of the frame, a pair of spiders mounted upon each sub-shaft, one adjacent each end of the same, a stub shaft pivotally mounted upon the end of each arm of each of the spiders, a plane member arranged between the arms of each pair of spiders and mounted at the ends upon the adjacent stub shafts, a crank arm formed at the inner end of each of the inner ones of said stub shafts, power means for imparting rotary motion to said main shaft, and means for simultaneously rocking the cranks to change the working positions of the planes to cause the same to impart vertical or horizontal movement to the structure.

3. An aeroplane of the character described, comprising a main frame, a revolute main power shaft extending through and

- having each end projecting beyond one side of said frame, substantially setting up a pair of sub-shafts, one on each side of the frame, a pair of spider members mounted upon each 5 sub-shaft, one adjacent each end of the same, each spider including a plurality of radially extending arms, a stub shaft mounted in the end of each arm of each pair of spider members, a plane member positioned between the 10 arms of each pair of spider members and mounted at the ends upon the adjacent stub shafts, a crank member formed upon the inner ones of the stub shafts, an eccentric body loosely journaled on each sub-shaft adjacent 15 the inner end thereof, an eccentric ring surrounding each body, radially extending arms carried by each ring, each engaging one of said cranks at its outer end, manually controlled means for oscillating each eccentric 20 to cause the oscillation of said cranks and plane members for changing the operating position of the planes, and power means for transmitting rotary motion to the sub-shafts.
- 25 4. An aeroplane of the character described, comprising a main frame, a revolvable main power shaft extending through and having each end projecting beyond one side of the frame, substantially setting up a pair of sub-shafts, one on each side of the frame,
- 30

a pair of spider members mounted upon each sub-shaft one adjacent each end of the same and having a plurality of radially directed arms, a stub shaft mounted in the end of each arm of each pair of spider members, a 35 plane member positioned between the arms of each pair of spider members and mounted at the ends upon the adjacent stub shafts, a crank member formed upon the inner ones of the stub shafts, an eccentric body 40 loosely mounted on each sub-shaft adjacent the inner end of the same, an eccentric ring, surrounding each body, radially extending arms carried by each ring 45 each engaging one of said cranks at its outer end, a sprocket wheel fixed to each eccentric body concentric with the shaft supporting the same, a sprocket wheel mounted upon the frame adjacent each eccentric body carried wheel, sprocket chains connecting each body 50 carried wheel with an adjacent sprocket wheel, a crank member controlling each frame carried sprocket wheel for shifting through the medium of the eccentric bodies, the eccentric rings, arms and crank members, 55 the working positions of said planes, and power means for transmitting rotary motion to said sub-shafts.

In testimony whereof I affix my signature.
JOHN B. MACFARLAND.
